UNITED STATES PATENT OFFICE.

ALBERT BIE, OF WINTERTHUR, SWITZERLAND, ASSIGNOR TO BUSCH-SULZER BROS.-
DIESEL ENGINE COMPANY, OF ST. LOUIS, MISSOURI, A CORPORATION OF MISSOURI.

ENGINE-CYLINDER.

1,226,630.

Specification of Letters Patent.

Patented May 22, 1917.

Application filed February 2, 1915. Serial No. 5,622.

To all whom it may concern:

Be it known that I, ALBERT BIE, a citizen of the Kingdom of Norway, residing in Winterthur, Switzerland, have invented a new and useful Improvement in Engine-Cylinders.

This invention is an improvement in cylinders of internal combustion engines, more especially constant pressure engines of the Diesel or similar types, the object being to provide a construction which combines strength and freedom from expansion stresses with convenience in taking apart and improvement in the water-cooling action.

In the accompanying drawings:

Figure 1 is a longitudinal section through a cylinder embodying the invention; and

Fig. 2 is a cross-section through the same.

The drawing shows a two-cycle Diesel engine cylinder comprising an inner or liner section *a* and an outer or jacket section *b*, cast separately and having lateral scavenging and exhaust ports *d* and *e*, the inner section having lateral bearing on the jacket at the region of said ports and also at the outer end, where the liner is formed with a flange *v* closing the cooling space *w* between the sections at this end.

The piston *l* operates in the liner, which contains the combustion chamber, the end wall *o* of the latter being united in one piece with the liner and provided with suitable valve openings *f* and *g* from which project integral parallel hollow valve sockets *m* and *n*. A head *c* is formed in one piece with the jacket and has openings for the reception of said valve sockets, which pass through the head and are designed to receive fuel-injection and starting-air valves, *x* and *z*, which latter are of known construction and for this reason not shown in detail. The liner with its end wall and valve studs may be removed from the jacket and head at the crank or lower side, which is a substantial advantage, particularly in marine installations where removal upwardly may necessitate tearing up of decks. Furthermore, the liner and combustion chamber end wall, being separate from the jacket and head, may be readily finished off smooth on their outer as well as their inner surfaces, thus producing a more perfect contact between the metal and cooling water

and rendering adhesion of scale more difficult and its removal easier.

The end wall *o* of the liner section bears inwardly of its circumference against the head, as shown by the raised bearing surfaces *k* adjacent the valve sockets. By this mode of supporting the liner section toward the middle of its end wall against the pressure in the combustion chamber, the wall *o* can be made of less thickness than would otherwise be the case, and thus, by reducing the differences in temperature between its inner and outer portions, the corresponding thermal tensions may be decreased. Longitudinally the liner is free to expand toward the crank shaft, thereby further lessening the stresses due to thermal expansion in the working of the engine.

The head *c* may be formed with strengthening and flow-directing partitions *s* and *t* for the water circulating therein. The chambered structure thus constituted comprises the outer end wall of the head, an inner transverse wall *3*, against which the liner section has its end bearing, the encircling lateral wall, and internal ported walls *t* uniting the outer and inner transverse walls, the openings for the valve sockets being inside of these internal walls *t*. In the particular arrangement shown the cooling water enters the lower portion of the cooling space *w* at one side through the port *h*, passes upwardly and over the top of the liner to connection *r*, thence into the cooling spaces in the upper part of the head and out at *i*. It will be understood that the drawing does not purport to show features and details unessential to the invention, and that, for example, wherever joints should be made tight in practice the usual expedients may be resorted to in actual construction.

What is claimed as new is:

1. In an internal combustion engine cylinder, the combination of a jacket, a head united therewith, and a liner having an end wall with valve openings and parallel valve sockets extending therefrom through the head, said wall having bearing against the head adjacent said valve sockets and the liner member with the valve sockets being removable from the jacket at the crank side.

2. An internal combustion engine cylinder, comprising a jacket section having an

- integral chambered head with valve socket openings, said head having an outer end wall and an inner transverse wall with a water chamber between them, and a liner section having an integral end wall bearing against the inner wall of the head and integral parallel valve sockets received in the openings therefor, the liner section with its end wall being removable from the jacket at the crank side.
3. An internal combustion engine cylinder, comprising a jacket section having an integral chambered head, said head having an outer end wall and an inner transverse wall with an intervening water chamber, the said walls having valve socket openings toward their central portions, and a liner section having an integral end wall with integral parallel valve sockets received in said openings, the end wall of the liner section and the inner wall of the head having abutting raised seats surrounding and adjacent the valve sockets.

4. An internal combustion engine cylinder, comprising a jacket section having an integral chambered head, said head having an outer end wall and an inner transverse wall spaced therefrom, an encircling wall and ported internal walls connecting said inner and outer walls, and a liner section having an integral end wall with integral parallel valve sockets received in openings in the head and passing inside of said internal walls, the end wall of the liner section bearing against the inner wall of the head and the liner section with its end wall being removable from the jacket at the crank side.

In testimony whereof, I have signed this specification in the presence of two witnesses.

ALBERT BIE.
